[57] CLAIM

The ornamental design for luggage, substantially as shown and described.

DESCRIPTION

FIG. 1 is a top plan view of luggage showing my new design;

FIG. 2 is a right side elevational view thereof;

FIG. 3 is a front elevational view thereof;

FIG. 4 is a rear elevational view.

FIG. 5 is a left side elevational view thereof.

FIG. 6 is a bottom plan view.

FIG. 7 is a perspective view of an alternate embodiment thereof which is identical to the embodiment shown in FIGS. 1 to 6 except that the entire luggage body has a smooth texture as opposed to the ribbed texture shown in FIGS. 1 to 6.
